CLAIM

An ornamental design for a disinfecting device, as shown and described.

DESCRIPTION

FIG. 1 is a top, front, right perspective view of a disinfecting device, showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken lines in the FIGURES depict portions of the disinfecting device that form no part of the claimed design.
